UNITED STATES PATENT OFFICE.

THOMAS I. RANKIN, OF PHILADELPHIA, PENNSYLVANIA, ASSIGNOR TO
ABRAM COX STOVE COMPANY, OF PHILADELPHIA, PENNSYLVANIA,
A CORPORATION OF PENNSYLVANIA.

DESIGN FOR A HEATING-STOVE.

SPECIFICATION forming part of Design No. 35,459, dated December 17, 1901.

Application filed August 21, 1901. Serial No. 72,854. Term of patent 7 years.

To all whom it may concern:

Be it known that I, THOMAS I. RANKIN, a citizen of the United States, residing in Philadelphia, Pennsylvania, have invented and produced a certain new and original Design for a Heating-Stove, of which the following is a specification.

My design for a heating-stove is clearly illustrated in the accompanying drawing, which 10 represents the stove in perspective.

The essential feature of the design is the ornamentation found on the base, front plate, and dome-section of the stove.

K is the base of the stove, carrying the ash-15 pit structure, the ash-pit door k at the front being ornamented with floral scrolls.

k' k' are the feet which support the base of the stove, each foot being ornamented with a shell-scroll.

20 Each side of the base of the stove is ornamented with scrollwork, and the upper surface of each foot-rest k² is ornamented by scrollwork in keeping with the general design.

The body K' of the stove is plain, having 25 an ornamental front plate K², to which the fire-door K³ is pivoted. The fire-door has a

name-plate and below it a rosette. On each side of the door is a long ornamental scroll, and at the top of the door is a fan-like scroll, and at the bottom of the door is a scroll. 30

Surrounding the fire-door opening is a series of scrolls, and below the door is a central fleur-de-lis ornament surrounded by scroll-work ornamentation in keeping with that of the door. 35

The dome K⁴ has a base-section K⁵, ornamented by scrollwork, and an upper portion K⁴, ornamented with fleur-de-lis, shell, and scroll ornamentation. Between the two sections is a narrow border having ribbed ornamentation thereon. 40

I claim—

The design for a heating-stove, as herein described and as illustrated in the accompanying drawing. 45

In testimony whereof I have signed my name to this specification in the presence of two subscribing witnesses.

THOMAS I. RANKIN.
